UNITED STATES PATENT OFFICE.

WILLIAM McKEAN McCLINTOCK, OF ST. PAUL, MINNESOTA.

LIGHTNING-ARRESTER.

1,189,272.

Specification of Letters Patent.

Patented July 4, 1916.

Application filed August 6, 1909. Serial No. 511,617.

To all whom it may concern:

Be it known that I, WILLIAM M. McCLINTOCK, of St. Paul, Ramsey county, Minnesota, have invented certain new and useful 5 Improvements in Lightning-Arresters, of which the following is a specification.

The object of my invention is to provide a lightning arrester adapted particularly for the circuits of railway signaling devices 10 and the object of the invention is to provide an arrester of simple, durable construction and one which will ground the heavy charge on the line wires resulting from induction or other causes during a severe 15 electrical storm.

The invention consists generally in a line circuit having terminals and a ground interposed between the terminals and provided with a block of carborundum, which 20 will allow only a slight leakage of a current of low voltage, but will become broken down and ground a current of high voltage such as would be induced during an electrical storm.

25 In the accompanying drawings, forming part of this specification, Figure 1 is a longitudinal sectional view of a lightning arrester, embodying my invention, Fig. 2 is a side view of the same, Fig. 3 is a top view, Fig. 4 is a side view of a modified construction.

In the drawing, 2 represents a block of insulating material and 3 and 4 binding screws having nuts 5 and 6 and forming the 35 terminals of an electric circuit, a metallic plate 7 being interposed between the binding screws and closing the circuit between them.

8 is a third binding screw having nuts 9 40 and 10 and a plate 12 between which and the plate 7 an insulating ring 13 and a block 14 of carborundum material is arranged, the plate 12 being normally insulated from the plate 7 against the passage of a current 45 of low voltage, such as would be generally used in the circuit of the signaling device.

A carborundum block is firmly clamped between the plate 7 and the plate 12 by 50 means of the nut 9, engaging the threads of the screw 8. By tightening this nut upon the screw the carborundum block 14 may be held between the plates 7 and 12 with any desired pressure. The screw 8, when the device 55 vice is in use will be connected with the ground by a suitable conductor, not shown.

The resistance of the carborundum block is sufficient to prevent the passage of the normal current, but during an electrical storm when the air is heavily charged with 60 electricity and currents of high voltage will be induced in the circuit, the carborundum block will become a conductor to such an extent that it will ground these high tension currents and prevent them from passing along the wires to the signaling instrument. This carborundum block is molded by a suitable process, and is composed entirely of a conducting material, and is of such a nature that it will offer sufficiently 70 high resistance to prevent the grounding of a normal current but will ground a current of high voltage, such as a bolt of lightning, and prevent such current from passing through the arrester to the instrument. 75

In Fig. 4 I have shown a modified construction, which consists in providing a block 15 having a hole therethrough for the ground screw 8 and taking the place of the 80 insulating ring 13. The functions of this block will be substantially the same as described with reference to the block shown in Figs. 1 and 2. The device may be made of any suitable size and the carborundum 85 block varied in dimensions according to the size of the arrester and the purpose for which it is to be used.

The crystallized carborundum is broken up into grits of various grades which are 90 separated by means of a screening process. These grits are mixed with a small percentage of sodium silicate or other binding material, shaped in proper molds under great pressure and finally baked at high 95 temperature. The latter processes do away with the binding substance and use a sufficiently high temperature to recrystallize the carborundum.

The particles of carborundum lie in close 100 contact with one another in the block and being of non-conducting material will resist the passage of a current of low voltage. When, however, the arrester is subjected to abnormal conditions, as when the line is struck by a bolt of lightning, the particles of carborundum will lose their resistance to a certain extent and will become 105 a conductor for a current of high voltage.

I claim as my invention:

A lightning arrester comprising an insulating block, a conducting plate seated

thereon, a binding screw adapted for a ground connection mounted in said block and passing through said plate and insulated therefrom, a second conducting plate 5 mounted on said binding screw and overhanging said first named plate and insulated therefrom, a block of high resistance material interposed between said conducting plates and in close contact therewith, 10 said block having sufficient resistance to prevent the passage of a normal current therethrough but offering a decreased resistance to the passage of a current of high voltage and forming temporarily a conductor therefor to said binding screw, and terminal binding screws mounted in said block and in circuit with said first named conducting plate.

In witness whereof, I have hereunto set my hand this 29th day of July 1909.

WILLIAM McKEAN McCLINTOCK.
